UNITED STATES PATENT OFFICE.

JOSEPH B. KASSER AND MORRIS KASSER, OF SAN FRANCISCO, CALIFORNIA.

AUTOMATIC COMPARTMENT-INFLATER FOR SHIPS.

1,135,902.

Specification of Letters Patent. Patented Apr. 13, 1915.

Application filed June 8, 1914. Serial No. 843,894.

To all whom it may concern:

Be it known that we, JOSEPH B. KASSER and MORRIS KASSER, citizens of the United States, and residents of the city and county of San Francisco, State of California, have invented a new and useful Improvement in Automatic Compartment-Inflaters for Ships, of which the following is a specification.

Our invention relates to automatic compartment inflaters for ships wherein a valve and deflected bags operate in conjunction with a source of compressed air; and the objects of our invention are first, to provide improved means for automatically inflating a bag within a ship's compartment when the said compartment has been perforated or punctured below the water line; second, to provide improved means for preventing the flooding of the compartment punctured; and third, to provide means for indicating the compartment punctured.

We accomplish these several features by means of the device disclosed in the drawings forming a part of the present specification wherein like characters of reference are used to designate similar parts throughout the said specification and drawings and in which—

Figure 1 is a broken sectional plan view of a vessel taken below decks and disclosing the air receiver, and the connections from the air receiver to the various compartments. Fig. 2 is a broken elevation of a vessel disclosing the connections from the main air pipes to the lower compartments. Fig. 3 is a broken vertical sectional view of one of the compartments disclosing a deflated bag therein, the float valve therein, and the manner in which the bag is connected to the valve on the air pipe, and the means secured to the valve stem and arranged to indicate the compartment punctured. Fig. 4 is a view similar to Fig. 3 but disclosing the bag when inflated. Fig. 5 is a broken detailed view of the indicator on one end of the valve stem which indicates that the compartment to which it is attached is punctured and that the valve is opened in that compartment and compressed air is being forced into the bag. Fig. 6 is a vertical longitudinal section of one of the compartments disclosing the manner in which an inflated bag fills the compartment, the position of the float, when the air is turned off, being indicated in dotted lines. Fig. 7 is

a vertical sectional view through one of the valves disclosing the same in an open position, and Fig. 8 is a transverse sectional view taken through one of the valves disclosing the manner in which the valve stems extend beyond the valve and into the interior of the hold to an indicator.

The numeral 1 is used to designate the hull of a ship divided into the compartments 2. A suitable compressed air receiver 3 is secured in any suitable portion of a ship and is provided with compressed air from a compressor, not shown, through the pipe 4. The pipes 5 lead from the receiver 3 to the compressed air pipes 6. From the pipes 6, are extended air pipes 7 leading to the several compartments 2 of the ship. The pipes 7 are provided with lateral extensions 8, which extend into the compartments 2 and terminate in the valves 9, having the stems 10 thereof extended in both directions.

A deflated bag 12 is secured within the compartment and to the valve 9. A lever 14 is secured to one end of the valve stem 10 and is provided with a suitable float 15. The other end of the stem 10 extends beyond the wall of the compartment 2 and has an indicator 16 secured thereto, which is adapted to indicate the open and closed positions of the float 15 and lever 14 secured to the valve 9.

The operation is as follows: Should a puncture occur in the outer wall of the compartment 2 at any point below the water line, the water could flow through the puncture and elevate the float 15, which would in turn raise the lever 14, operate the stem 10 and open the valve 9 causing the compressed air to enter and inflate the bag 12 and nearly fill the compartment 2, as illustrated in Figs. 4 and 5 of the drawings, thus forcing out of the compartment 2 nearly all of the water which flowed into it through the puncture, and thereby restoring the buoyancy of the said compartment.

The normal positions of the parts are disclosed in Fig. 3 of the drawings, in which case the indicator 16 will point to the word "Closed". When the float 15 is elevated by means of water in the compartment 2, the indicator 16 will point to the word "Open". By this means, the location of a puncture or rupture of a ship's bottom may be easily located, as well as the approximate extent, thereof. For instance, if the vessel had impinged on a rock and had punctured a num-

ber of plates or compartments 2, the float 15 would be raised in every compartment 2 to which water had been admitted and those compartments punctured would be indicated 5 by the indicator 16, which would point to the word "Open" on the outer side of the compartment 2 and the inside of the ship, clearly indicating which compartments had been punctured and were being filled with air, and 10 the approximate extent of the damage. In this manner, after a shock or collision, it is very easy to determine the approximate extent and location of the damage occasioned by such shock. It is also obvious, that while 15 the bags 12 are normally deflated and away from the outer plates of the compartment 2, that such bags 12 are not exposed to injury by reason of the punctures to the said plates and even were most of the outer plates en- 20 tirely removed or carried away without destroying the bags 12, it is evident that the presence of water would cause each float 15 below the water line to rise and admit air from the compressed air pipes 8 to the bags 25 12. The result would then be, that in place of a hole in the ship a pneumatic cushion composed of the bags 12 would be automatically brought into place and the buoyancy of the vessel would be sustained by reason 30 of the said inflated bags taking the place of the destroyed compartments.

It is obvious from the foregoing that we have provided improved means for automatically inflating ship compartments when the 35 said compartments have been punctured or perforated below the water line and we have also provided means whereby the approximate extent and location of the damage to the outer plates of a ship, resulting through 40 collision or other serious impact, may be indicated.

Having thus described our invention what we claim as new and desire to secure by Letters Patent is—

45 1. An automatic compartment inflater comprising a compressed air pipe connected to the compartment; a bag secured within the compartment and to the pipe; and means secured to the pipe and adapted to automatically cause compressed air from the pipe to inflate the bag when the said compartment is flooded.

50 2. An automatic compartment inflater comprising a compressed air pipe connected to the compartment; a valve secured to the end of the compressed air pipe; a bag secured within the compartment and to the valve on the compressed air pipe; and means adapted to be operated by water within the 55 compartment and to open the valve and inflate the bag in the said compartment.

3. An automatic compartment inflater comprising a compressed air pipe connected with the compartment; a valve secured to the end of the compressed air pipe; a bag secured to the valve; and means adapted to be operated by the entrance of water within the compartment for the purpose of inflating the bag from the compressed air pipe. 65

4. An automatic compartment inflater 70 comprising a compressed air pipe connected with the compartment; a valve secured to the end of the compressed air pipe; a bag secured to the valve; means adapted to be operated by the entrance of water within the 75 compartment for the purpose of inflating the bag from the compressed air pipe; and means for indicating that the bag within the compartment is being inflated.

5. An automatic compartment inflater 80 comprising a compressed air pipe connected with the compartment; a valve secured to the end of the compressed air pipe; a bag secured to the valve; means adapted to be operated by the entrance of water within the 85 compartment for the purpose of inflating the bag from the compressed air pipe; and means secured to the valve and adapted to indicate that the said valve is open.

6. An automatic compartment inflater 90 comprising a compressed air pipe connected with the compartment; a valve secured to the end of the compressed air pipe; a bag secured to the valve; means adapted to be operated by the entrance of water within 95 the compartment for the purpose of inflating the bag from the compressed air pipe; and an indicator secured to the valve and extending to the outside of the compartment and adapted to indicate that the valve is open. 100

7. An automatic compartment inflater comprising a compressed air pipe extending into the compartment; a valve secured to the air pipe and having a stem extending beyond the compartment; a bag within the 105 compartment and secured to the valve; a lever having a suitable float on the end thereof secured to the valve stem and adapted to open the valve and inflate the bag when water enters the compartment; and an indicator on the end of the stem beyond the compartment adapted to indicate the open and closed position of the valve. 110

In witness whereof we hereunto set our signatures in the presence of two subscribing witnesses. 115
